W. L. TAYLOR

PAPER PASTING MACHINE

Filed Aug. 7, 1922

INVENTOR:

William L. Taylor

BY

Acme
ATTORNEYS.

UNITED STATES PATENT OFFICE.

WILLIAM L. TAYLOR, OF CINCINNATI, OHIO.

PAPER-PASTING MACHINE.

Application filed August 7, 1922. Serial No. 580,056.

To all whom it may concern:

Be it known that I, WILLIAM L. TAYLOR, a citizen of the United States, and a resident of Cincinnati, in the county of Hamilton 5 and State of Ohio, have invented certain new and useful Improvements in Paper-Pasting Machines, of which the following is a full, clear, and exact description, reference being had to the accompanying drawings, forming 10 part of this specification.

My invention relates to machines for pasting sheets of paper together with an asphalt or like bituminous binder for the purpose of moisture-proofing the paper, and relates 15 more particularly to devices for providing lines of non-asphaltic material along the edges or in bands running lengthwise of the pasted web.

The object of providing for these bands 20 is fully set forth in several co-pending applications of my own, among them application, Serial No. 551,018, filed April 10, 1922.

In this application I describe a modified apparatus over the one shown in the drawings 25 of the above noted application having as an object the reducing of the chances of asphalt getting into the selected bands or lines on which it is desired to deposit a stream of cement or other interposed stream 30 not having the tacky consistency of asphalts which are of value in binding webs of paper together.

I accomplish the object of my invention 35 by that certain construction and arrangement of parts to be hereinafter more specifically pointed out and claimed.

In the drawings,

Figure 1 is a side elevation of a set of 40 rolls and tank as used by me, omitting the mountings and driving connections which contain nothing novel.

Figure 2 is a perspective view showing the coating roll and one form of special wiper for the grooves thereof.

The apparatus comprises a storage roll 1 for the one web of paper 2, and the storage roll 3 for the other web of paper 4. The paper, when pasted, is wound on the roll 5.

I provide the tank 6 containing molten 50 asphalt, in which revolves the roller 7, said roller being so set as to dip in the asphalt bath. Mounted so as to contact with the roller 7 is the coating roller 8.

The paper passes between two rolls 9 and 55 10 where it is pressed together and the web

2 comes from its storage between the rolls 9 and 8 and thence around the roll 9 and between it and the roll 10. The web 4 passes through a device for depositing lines or bands of material other than tacky asphalt, 60 and thence between the rolls 9 and 10 where it is united with the web 2. I have omitted a showing of the line depositing device, as this may be of any type, such as is indicated in my application above referred to. 65

It will be noted that in this device I have removed the coating roll by one step from the asphalt tank. I find that this is necessary in using such asphalts as will give a proper action in binding the webs of paper 70 together. A two-step removal might be advisable in some cases, it being the principal object to prevent excess of asphalt traveling up around the roller 7 and getting directly on the paper. 75

In the rollers 8 I have formed grooves 11, and at the ends thereof I have formed grooves or cut away portions 12. These portions naturally do not wipe the roller 7 and hence get no direct coating of asphalt 80 from the roller 7. The paper web is thus intended to have no asphalt coating along lines defined by these grooves or cut away portions.

I find that I have to use a special wiper 85 in order to insure a proper definition to the margin line of the asphalt coating at each side of the lines or bands and to prevent considerable coating of the said lines.

I have shown but one wiper and it will 90 be understood that all wipers will be formed on the same principle. In the form shown there are cross pieces 12^a, which lie over the roller 8 along the margins of the grooves. The pieces 12^a may be ears turned 95 out at the top of the tubular scraper to be described below and clean off the edges of the roll at a point beyond the contact of the paper web 2 therewith, as indicated by the arrows of revolution. The pieces 12^a impinge against the surface of the roller along the edges of the grooves and dam up the accumulated asphalt thereon, which flows and is drawn down into the grooves to be then scraped away by the lower edge of the 100 trough mouth.

In addition to the scraper I form a trough or tube 13, which is of a width to lie in the groove, and this trough has the part defining the lower edge of its mouth 110

lying in the groove and extending to the base thereof, as at 14. Thus the trough scrapes off all asphalt which may get into the groove and prevent an accumulation there. This asphalt runs back into the tank through the trough, which may be mounted in the tank as at 15.

It will be noted that without the use of some form of scraper to take asphalt out 10 of the groove, there will be such an accumulation of asphalt there as will rapidly fill it up. The roller 8 does not dip in the tank, so that accumulation might wash or melt off, and the asphalt in my experience 15 fills the grooves even more rapidly because of the action of the margin scraper.

The margin scraper is necessary, however, since the flow of asphalt on the paper is such as to extend across the desired line 20 of non-asphalt coated nature, and hence the quantity of asphalt along the margins thereof must be carefully regulated as to accumulation.

The exact construction of the scraper device or of the grooves in the roller are not 25 considered essential by me, and I have merely attempted to show and describe one form thereof.

Having thus described my invention, what 30 I claim as new and desire to secure by Letters Patent, is:—

1. A mechanism for coating paper or the like with asphalt or the like, comprising a tank for asphalt, a roll revoluble in a 35 position to dip into said tank, and at least

one additional roll wiping said first mentioned roll, and adapted to engage a traveling paper web, said roll having peripheral grooves so as to form non-asphalted lines on the paper, and means for wiping the margins of said grooves, and means for wiping the entire grooves so as to prevent accumulation of asphalt therein. 40

2. A mechanism for coating paper or the like with asphalt or the like, comprising a tank for asphalt, a roll revoluble in a position to dip into said tank, and at least one additional roll wiping said first mentioned roll, and adapted to engage a traveling paper web, said roll having peripheral 45 grooves so as to form non-asphalted lines on the paper, and means for wiping the margins of said grooves, and means for wiping the entire grooves so as to prevent accumulation of asphalt therein, said means comprising a conduit to cause such asphalt 50 to flow back into the tank.

3. A mechanism for coating paper or the like with asphalt or the like, comprising a tank for asphalt, a roll adapted to receive asphalt on its surface from said tank, said roll being revolvable, and having grooves cut peripherally therein so as to form non-asphalted lines on the paper, means for wiping the margins of said grooves, and means for wiping out the side walls and base of 60 said grooves, both of said means in combination with a conduit for guiding said wiped asphalt away from said grooved roll. 65

WILLIAM L. TAYLOR.
